Tenyson Steyson

UNITED STATES PATENT OFFICE

JOHN PARSONS, OF MONTCLAIR, NEW JERSEY, ASSIGNOR TO PAN-ROSS LABORATORIES, INC., OF NEW YORK, N. Y., A CORPORATION OF NEW YORK

SELF-LIGHTING CIGARETTE AND IGNITION BAND THEREFOR

Application filed October 30, 1925, Serial No. 65,723. Renewed November 15, 1930.

My invention relates to new and useful improvements in self-lighting cigarettes and ignition bands therefor. The object of my invention is to provide an ignition band suitable for application to the lighting end of a cigarette which will enable the cigarette to be lighted by striking same upon a suitable abrasive surface.

In my invention, I associate with a cellulose or fibrous substance such as paper with an additional oxidizing substance and provide the same with a layer of a fulminating material. This fulminating substance is made preferably with a nitrocellulose solution base, as the same then has desirable waterproofing qualities. Preferably, also, I employ on the side of the paper opposite to the fulminating surface an adhesive, and I have found that a suitable adhesive

20 may be formed of nitrocellulose solution, which not only will function as an adhesive in affixing the ignition band to the end of the cigarette, but is itself a ready transmitter of combustion and self-combustible.

25 I thus provide a fuse band which may be prepared in ribbon form and which may be applied by suitable mechanism in strips to the end of the cigarettes. The ignition band can be prepared economically, and is of it-
30 self sufficiently flexible to permit being prepared in ribbon form and affixed to the cigarette wrapping paper either before or after the same has been filled with tobacco and rolled into cigarettes. The adhesive, if ni-

35 trocellulose solution or similar substance be used, will be of a substance not homogeneous with the paper base. Thus when the adhesive is touched with a solvent, it will function as an adhesive without tending to unduly soften

40 the band itself. The band preferably is applied to the outside of the cigarette and will have on its exterior surface a layer of a fulminating substance. When this is contacted with suitable abrasive surfaces, it will ignite

45 the paper, which will burn readily, being impregnated with an oxidizing substance. The paper has the necessary coal-forming prop-
50 erty to surround the cigarette and the tobacco filling at its end with a ring of fire,

My invention consists of the novel devices described herein and shown, but it is to be understood that I have set forth my invention in its preferred form and the scope of the invention is not to be understood as limited to the form described but is as set forth in the claims appended hereto.

Of the drawings,

Figure 1 is a view of a self-lighting cigarette provided with my preferred form of ignition band;

Fig. 2 is an enlarged detail and illustrative end view of same; and

Fig. 3 is a view of a section of my ignition band prepared in ribbon form prior to being affixed to cigarette wrapping paper.

In preparing my self-lighting cigarettes and ignition band to be affixed thereto, I take, preferably, a cellulose isolated from wood, such as a filter paper, and submit same to an extra oxidizing substance, preferably by treating the paper with a ten per cent dilute solution of potassium nitrate. This impregnation may be accomplished either when the paper is being made or after it has been made. Sheets of paper thus prepared, free from all moisture, are then coated with a fulminating substance which is spread on thinly over the entire surface. If it is desired to apply adhesive at that stage in the operation, an adhesive may be spread over the reverse side of the treated paper. I have found that nitrocellulose solution serves admirably as an adhesive for this purpose. It also moistureproofs the side of the paper to which it has been applied. If the fulminating substance likewise is prepared with a base of nitrocellulose solution and is spread on the other side of the paper as described, both sides of the paper thus will be treated with a moistureproofing dope. The treated paper and the entire ignition band therefore will be rendered impervious to moisture, and, when applied to cigarettes, will make the self-lighting qualities of the cigarettes lasting and permanent.

The paper, when spread with fulminate and with adhesive as above described, may then be cut into suitable strips of desirable width and length and pasted around the ciga-

rette, or the paper so prepared may be cut into ribbons of suitable widths and lengths and wound on reels or bobbins and applied by suitable machinery to the cigarette wrapping paper before or during the course of the preparing, wrapping or filling of the cigarette. The strips may be applied to the cigarette wrapper at intervals so as to come out at the end of the cigarette when rolled and cut.

10 In the drawings, a cigarette of the usual form is shown composed of cigarette wrapping paper 1 with tobacco-filled center 2. At the lighting end of the cigarette is exteriorly applied an ignition band 3. This ignition band is composed of a thin layer of fulminating substance 4 which preferably should have as a base for mixing the fulminating materials a nitrocellulose solution or similar substance which is self-combustible and has desirable waterproofing qualities. The ignition band has a base made of paper or other similar material 5, and the band is affixed to the cigarette paper by adhesive 6. This adhesive is made of nitrocellulose solution which is a self-combustible material and a transmitter of combustion, which therefore aids the oxidized paper base in its function of igniting the cigarette. The ignition band may be prepared prior to its application to the cigarette as above described and may consist of a ribbon 7 which is formed with an oxidized paper base and a fulminate layer on one side. Preferably, also, the ribbon may be provided 35 with a layer of adhesive 4', and, as stated, nitrocellulose solution is most suitable for this purpose of the adhesive. The ribbon thus prepared is flexible and may be wound on suitable reels or bobbins such as 8. The 40 ribbon is ready prepared and may be applied to the cigarette by merely applying a slight amount of solvent to the adhesive. This solvent will not permeate the entire band, as the paper base and the adhesive will not 45 be of homogeneous materials.

I have described and shown my ignition band used and adapted to be used with self-lighting cigarettes. It is, of course, equally suitable for use with cigars and little cigars, and it is also to be understood that it is capable of being used in many other ways, and that my invention is not to be considered as limited to the particular use described.

50 What I claim is new and desire to secure by United States Letters Patent is:—

1. An ignition band of the character described comprising a paper base containing an extra oxidizing ingredient, a layer of moistureproofing fulminating substance, and a moistureproofing adhesive spread on the respective sides of said base.

2. In an ignition band, the combination of 60 laminated layers of a fulminating substance, a paper base containing an extra oxidizing

ingredient, and a combustible adhesive substance.

3. An ignition band comprising the combination of a paper base containing an extra oxidizing ingredient, a layer of fulminating substance, and a nitrocellulose solution adhesive. 70

4. An ignition band comprising the combination of a paper base containing an extra oxidizing ingredient, a layer of fulminating substance having a nitrocellulose solution base, and a nitrocellulose solution adhesive. 75

5. The method of preparing an ignition band of the character described comprising treating a paper substance with an extra oxidizing substance, spreading on one side thereof a fulminating material and applying a combustible adhesive substance to the other side. 80

6. The method of preparing an ignition band of the character described comprising treating a paper substance with an extra oxidizing substance, spreading on one side thereof a fulminating material and applying a nitrocellulose solution to the other side. 85

7. The method of preparing an ignition band of the character described comprising treating a paper substance with an extra oxidizing substance, spreading on one side thereof a fulminating substance having as a base a moistureproofing material and applying an adhesive combustible waterproofing to the other side. 90

8. The method of preparing an ignition band of the character described comprising treating a paper substance with an extra oxidizing substance, spreading on one side thereof a fulminating material and applying a combustible adhesive to the other side. 100

9. The method of preparing an ignition band of the character described comprising treating a paper substance with an extra oxidizing substance, spreading on one side thereof a fulminating material and applying a combustible adhesive substance to the other side, and cutting same into ribbons. 105

10. The method of preparing an ignition band comprising treating a paper with a solution of potassium nitrate, and spreading on one side a fulminating substance and nitro-cellulose adhesive solution on the other side. 115

In testimony whereof, I have signed my name to this specification.

JOHN PARSONS. 120
